(57) **CLAIM**

The ornamental design for a protective armor, as shown and described.

DESCRIPTION

FIG. 1 is a front perspective view of a protective armor showing the new design.

FIG. 2 is a perspective rear view of the protective armor.

FIG. 3 is a front elevational view of the protective armor.

FIG. 4 is a back elevational view of the protective armor.

FIG. 5 is a left side elevational view of the protective armor, the right side being a mirror image.

FIG. 6 is a top plan view of the protective armor; and,

FIG. 7 is a bottom plan view of the protective armor.

The broken lines in the drawing depict environmental subject matter and form no part of the claimed design.
